CLAIM

The ornamental design for a fiber tip applicator, as shown and described.

DESCRIPTION

FIG. 1 is a top, front and left side perspective view of a fiber tip applicator showing our new design;

FIG. 2 is a left side elevational view thereof, the right side being a mirror image of that shown;

FIG. 3 is a top plan view thereof, the bottom being a mirror image of that shown;

FIG. 4 is a front elevational view thereof; and,

FIG. 5 is a rear elevational view thereof.
